UNITED STATES PATENT OFFICE.

LOUIS WOJIDKOW, OF BROOKLYN, NEW YORK.

DESIGN FOR A TEA-HOLDER.

SPECIFICATION forming part of Design No. 27,937, dated December 7, 1897.

Application filed October 20, 1897. Serial No. 655,863. Term of patent 31 years.

To all whom it may concern:

Be it known that I, LOUIS WOJIDKOW, a citizen of the United States, residing at Brooklyn, county of Kings, and State of New York, have invented and produced a new and original Design for a Tea-Holder, of which the following is a specification, reference being had to the accompanying drawings, forming part thereof.

Figure 1 is a side elevation of a tea-holder, showing my new design. Fig. 2 is a top view of the same; and Fig. 3 is a central longitudinal section thereof, the handle being broken away.

As shown in the drawings, the leading or material feature of my design consists of a bell-shaped body having flattened panel portions and a convexed bottom.

A indicates the handle of the tea-holder, and B the bell-shaped body of the same, the sides of which are formed of flattened panels b, which radiate from the handle e toward the edge of the body, while each panel is or-

namented by the representation of a tea-flower. The rim of the bell-shaped body is 25 provided with scallops b'.

D indicates the convex bottom, which is provided with a knob-shaped downwardly-extending projection C, said bottom having radial depressions or grooves e, that extend 30 from the projection C, while between the depressions or grooves are formed segmental convexed panels d.

Having described my invention, what I claim as new, and desire to secure by Letters 35 Patent, is—

A design for a tea-holder, substantially as herein shown and described.

In testimony that I claim the foregoing as my invention I have signed my name in presence of two subscribing witnesses.

LOUIS WOJIDKOW.
